Assistant Examiner — Joan E. Diehl

(74) *Attorney, Agent, or Firm* — Michael Best & Friedrich LLP

(57) **CLAIM**

The ornamental design for a bottle, as shown and described.

DESCRIPTION

FIG. 1 is a top perspective view of a bottle.

FIG. 2 is a bottom perspective view of the bottle shown in FIG. 1.

FIG. 3 is a left side view of the bottle shown in FIG. 1.

FIG. 4 is a right side view of the bottle shown in FIG. 1.

FIG. 5 is a front view of the bottle shown in FIG. 1.

FIG. 6 is a rear view of the bottle shown in FIG. 1.

FIG. 7 is a top view of the bottle shown in FIG. 1; and,

FIG. 8 is a bottom view of the bottle shown in FIG. 1.

The dash-dash broken lines represent portions of the article that form no part of the claimed design. The dash-dot broken lines represent boundaries of the claimed design and form no part of the claimed design. Any surfaces inside the bottle form no part of the claimed design.

1 Claim, 5 Drawing Sheets

Related U.S. Application Data

continuation of application No. 29/727,516, filed on Mar. 11, 2020, now Pat. No. Des. 937,679.
